LOADING RIG FOR CAULKING GUNS

Harry E. Jones, Cleveland, Ohio, assignor, by direct and mesne assignments, to Force-Flo, Inc., Cleveland, Ohio, a corporation of Ohio

Application April 27, 1951, Serial No. 223,243

5 Claims. (Cl. 226—125)

This invention relates to a loading rig for caulking guns, grease guns or the like.

In the loading of caulking guns, grease guns, etc., it is necessary to apply considerable force to the material. This may be done by superimposing a shallow piston on such material while in the original container, depressing the piston within the container, and causing or permitting the material to escape through an opening in the piston in or to which opening the gun to be loaded is affixed. The piston can be depressed within the container by mechanical means, producing thereby the desired movement of the material through the opening in the piston and into the barrel of the caulking gun, grease gun or the like.

Generally speaking, loading rigs of this type have in the past been applied or affixed to the container at its upper end, usually being clamped to the open end of the container just below the top chime. With such an arrangement, forces of large magnitude cannot be applied to the material within the container, this for the reason that under such conditions the container is likely to bulge, burst or collapse, particularly at the bottom chime. Therefore, prior systems for loading caulking guns, grease guns, etc. have in the main been designed to apply only moderate forces to the material within the container.

It is an object of the present invention to reinforce the container, particularly at the bottom chime, in such manner as to permit the application to the material within the container of forces of much greater magnitude than those heretofore contemplated. Another object is to provide for the dissipation of unexpended forces through parts of the rig in direct contact with the ground, the floor or the foundation on which the rig is placed during loading, using a base plate for the purpose. Another object is to provide a strong, sturdy assembly which may be applied as a unit to a standard container such as a five-gallon pail and which, by virtue of the incorporation in the assembly of two or more cooperating levers, will apply forces of very great magnitude to the material within the container. A further object is to provide new and improved means for holding the caulking gun, grease gun or the like in loading position in the apparatus.

Other objects and advantages of the invention will be apparent from the description which follows and from the accompanying drawings, in which Figure 1 is a vertical central section with parts in elevation along the longitudinal axis of the crosshead forming part of the loading rig. Figure 2 is a top plan of the loading rig of Figure 1 but with the actuating handle broken away for convenience in illustration. Figure 3 is a side elevation, seen from the right in Figures 1 and 2, with a caulking gun shown in position on the loading cylinder but with certain parts of the rig omitted and others broken away in order to show details. Figure 4 is a side elevation of the loading cylinder, seen from line 4—4 of Figure 2. Figure 5 is a horizontal section of the loading cylinder, with certain parts in plan, as seen from line 5—5 of Figure 4. Figure 6 is a fragmentary section, on an enlarged scale, show-

2

ing the collar at the top of the loading cylinder together with one of the cams and the cam-operating handle.

Figure 1 shows the loading rig of the present invention applied to a conventional container 1 filled with caulking compound, grease or the like, the same taking the form of a standard five-gallon pail from which the covering lid has been removed. Container 1 has at the closed end thereof the usual bottom chime 2. Within chime 2 is received a closely fitting circular shoulder 3 forming part of a raised pad 4 that is provided to support the end of container 1. Pad 4, which forms part of a circular foot-plate 5, also serves to center container 1 in relation to the foot-plate. By means of the foot-plate, particularly the chime-engaging shoulder 3 on pad 4 thereof, container 1 is reinforced against rupture or collapse while external force is being applied to it by the loading rig.

Forming part of base plate 5 are two opposed pairs of lugs 6 and 7, the lugs 6 receiving and holding the lower end of a pivotally mounted tie rod 8 and the lugs 7 receiving and holding the lower end of a pivotally mounted tie rod 9. The tie rods, which are threaded at their upper ends, form the principal fastening elements of the loading rig. Their threaded upper ends project through a cross-head applied to the open end of container 1. Surrounding the upper ends of tie rods 8 and 9 where they project through the cross-head are washers 10 and 11 against which seat knob-shaped hold-down nuts 12 and 13, respectively. The latter receive and cooperate with the threaded portions of tie rods 8 and 9. The cross-head is slotted as at 14 and 15 in such manner as to permit quick engagement and disengagement of the fastening elements.

The cross-head itself consists of the two slotted end blocks 18 and 19, a center block 20 having a centrally located circular hole 21 passing vertically therethrough, two left side pieces 22 and 23, and two right side pieces 24 and 25. At their outer ends, left side pieces 22 and 23 adjoin and are welded to the side faces of slotted block 18; at their opposite ends, they abut and are welded to the end face of center block 20. Right side pieces 24 and 25 are similarly welded to the side faces of slotted block 19 and the opposite end face of center block 20. Thus the cross-head consists of a built-up member that extends from one side to the other of the loading rig.

Passing vertically through and guided by the walls of hole 21 in center block 20 is an operating rod 26 of the nature of a piston rod. To its upper end, as by means of a set screw, is detachably affixed a retainer 27. To its lower end is welded a shallow piston 28 of such dimensions as to permit it to enter freely but without too much clearance into the open end of container 1. In a suitable peripheral groove, seen in Figure 1, piston 28 carries a gasket 29 which is formed as a strip by a process of extrusion and applied to piston 28 before the piston is inserted in container 1. Gasket 29 is of a material such as synthetic plastic, synthetic rubber, natural rubber or the like that is able to stand up under such chemical or physical action as may be manifested by the caulking compound, grease, etc. with which container 1 is filled.

Centrally located on opposite sides of the cross-head and welded to center block 20, left side pieces 22, 23 and right side pieces 24, 25 are two rather large side plates 31 and 32. Side plates 31 and 32 extend vertically in parallelism to each other in such manner as to flank operating rod 26. In the form shown, the side plates are polygonal in shape, their upper ends inclining downwardly from left to right as seen in Figure 1. Extending between and welded to side plates 31 and 32 is a horizontal plate 33, rectangular in shape, that is provided near its center with a vertically extending circular hole. Operating rod 26 passes through and is guided by the edges of such hole, as well as the hole 21 in center block 20. Thus there is little chance for operating rod 26

to tilt to one side or the other, although necessary clearance is of course provided.

Mounted on horizontal plate 33 is an upper coil spring 34 which is surmounted by a double washer assembly 35. By virtue of the presence thereon of oppositely extending integral tabs, the latter is of elongated configuration, the elongation appearing in Figure 2. Both spring 34 and washer assembly 35 surround operating rod 26, the spring biasing the washer assembly into contact with a horizontal pintle 36, headed over as at 36a, that constitutes a stop extending transversely between the uppermost portion of side plate 31 and the uppermost portion of side plate 32. In consequence of the non-central location of pintle 36 and the action of coil spring 34, washer assembly 35 assumes the inclined position shown in Figure 1, in which the edges of the washer assembly surrounding the hole therein bite into operating rod 26, thereby effectively precluding upward movement but nevertheless permitting limited downward movement of the operating rod.

Immediately below transverse plate 33 is a similarly shaped double washer assembly 37 that is biased toward horizontal position by an underlying coil spring 38 surrounding operating rod 26. At its upper end, spring 38 abuts washer assembly 37; at its lower end, it seats on center block 20. Like washer assembly 35, washer assembly 37 is provided with a central hole through which operating rod 26 passes. Such hole is only slightly larger than the diameter of the operating rod 26. Thus if washer assembly 37 is depressed at one end, it will bite into operating rod 26 much as does washer assembly 35.

Overlying one end of washer assembly 37 is a pin 39, best shown in Figure 2, which forms part of a forked lever made up of two spaced side members 41 and 42 through which passes a pintle 43. The latter extends horizontally between side plates 31 and 32. At its ends it is headed over as indicated at 43a. Pintle 43, which is stationary, thus serves as the fulcrum for the forked lever carrying pin 39. That end of the lever carrying pin 39 lies directly above the near end of washer assembly 37. At the opposite end of the lever, the two side members 41 and 42 merge and are spot-welded together to provide an outwardly extending portion 44 mounting a short pivot pin 45.

Pivot pin 45 is common to the forked lever just described, which is of the nature of an auxiliary lever, and an actuating lever 48, best shown in Figure 1, that is provided at its outer end with a grasping portion 49. Actuating lever 48 has the longer of its two arms extending away from operating rod 26 and the various elements which surround and engage it. The shorter of its two arms, which extends toward operating rod 26, is formed as indicated in Figure 2 of two side members 50 and 51 which encompass the outwardly extending portion 44 of the auxiliary lever carrying pin 39. A pin 52 forming the fulcrum for actuating lever 48 is carried by the upper end of an upwardly extending link 53 which at its lower end is mounted on a pintle 54, headed over as at 54a, that extends from one to the other of side pieces 24 and 25. On opposite sides of link 53, pintle 54 is provided with spacers 55 and 56, shown in Figure 2.

Since pivot pin 45 is common to the actuating lever and the auxiliary lever, a force applied to actuating lever 48 at the grasping portion 49 thereof will be communicated to the outwardly extending portion 44 of the auxiliary lever and, through the latter, to pin 39 overlying the end of washer assembly 37. By proportioning the parts as indicated in Figure 1, the very great mechanical advantage afforded by actuating lever 48 is multiplied by the auxiliary lever, with the result that a relatively small downward force applied to grasping portion 49 of actuating lever 48 is exerted as a downward force of vastly greater magnitude on the proximate end of washer assembly 37.

When, for example, a downwardly acting force is first applied to grasping portion 49 of actuating lever 48, the latter pivots about fulcrum 52, thereby moving common pivot pin 45 in an upward direction and, with it, the end 5 of outwardly extending portion 44 of the auxiliary lever. The latter, being fulcrumed on pintle 43, moves upward at its right-hand end and downward at its left-hand end as seen in Figure 1, thus causing washer assembly 37 to bite into operating rod 26. As the stroke is continued, the pressure on washer assembly 37 forces operating rod 26 downward. Being rigidly affixed to the lower end of operating rod 26, piston 28 is forced downward within container 1 by the movement imposed on operating rod 26 by the rod-engaging means mounted on the supporting elements that go to make up the cross-head.

Piston 28 is provided as shown in Figure 3 with at least one opening (two or more may be present) which is tapped to receive the end 61 of a loading cylinder 60 that is threaded for engagement with the tapped opening 20 in the piston. Loading cylinder 60 is characterized at its upper end by an annular flange 62 that has the effect of providing loading cylinder 60 with an enlarged portion facilitating reception of the discharge end of the barrel of a caulking gun or the like. Located on a suitably formed shoulder within annular flange 62 is a gasket 63 of synthetic plastic, synthetic rubber or some other suitable material against which bears the discharge end of the barrel of gun 64. Below annular flange 62 is a sliding collar 65 that rides on and conforms closely to the outer dimensions of loading cylinder 60.

Fastened to and extending upward from sliding collar 65 are clamping means for caulking gun 64, the same taking the form of two vertically extending straps 66 and 67. The latter are hooked inwardly at their upper ends 35 as indicated at 66a and 67a (Figure 3). Hooked ends 66a and 67a are adapted to engage the flange, designated 68 in the drawings, that forms part of the conventional caulking gun near its operating end. By removing the nozzle from caulking gun 64, locating the discharge end 40 of the barrel on the gasket 63 in the socket formed at the upper end of loading cylinder 60, and depressing sliding collar 65, the caulking gun may be held erect on and clamped in leak-tight relation to loading cylinder 60.

This is accomplished as indicated in Figures 4, 5 and 6 45 by providing two end cams 69 and 70 between annular flange 62 and sliding collar 65. Cams 69 and 70, which are provided with flats 69a and 70a, respectively, are secured to loading cylinder 60 by rivets 71 and 72. They are united by an operating handle 73 for simultaneous actuation. When a downward force is applied to the latter, cams 69 and 70 rotate out of the position shown into a position in which flats 69a and 70a no longer make contact with sliding collar 65. Instead, contact is made by the rounded parts of cams 69 and 70. Thus depressing operating handle 73 has the effect of depressing sliding collar 65 relative to loading cylinder 60, thereby clamping the loading gun firmly in the position shown in Figure 3.

In operation, a container filled with caulking compound, 60 grease or like material is freed of the covering lid and centered on pad 4 of foot-plate 5. Thereafter, the cross-head is applied in proper relation to the open upper end of the container, whereupon piston 28 will enter the container and will locate itself in contact or just out of contact with the top surface of the material in the container. Tie rods 8 and 9 are then swung into a position in which they enter slots 14 and 15 at the ends of the crosshead, after which hold-down nuts 12 and 13 are screwed down.

Thereafter the caulking gun 64 to be loaded is mounted as described on loading cylinder 60, being clamped in place by depressing handle 73. This establishes an open conduit between the discharge end of the barrel of the caulking gun 64, loading cylinder 60, and the interior of container 1. Thereafter, when piston 28 is depressed 70 within container 1, the material with which the container

is filled moves upward through loading cylinder 60 and into the open end of the barrel of caulking gun 64, all as indicated in Figure 3.

It is apparent that changes may be made in the loading rig of the invention without departing from the spirit thereof, as, for example, by substituting for the rod-engaging means shown in Figures 1, 2 and 3 a mechanism of different type. Preferably, however, the system that is used will be one wherein forces of small magnitude are multiplied and applied as forces of large magnitude to operating rod 26 and the piston 28 at its lower end. Other methods of holding the cross-head to the container may be devised and used, although that described above permits of the ready dissipation through the foot-plate of unexpended forces applied to the grasping portion of the actuating handle. It is also apparent that other means, including locking nuts and the like, may be used for attaching the gun to the loading cylinder. The preferred form of clamping means shown in Figure 3 may of course be replaced by other clamping means without departing from the inventive concept.

It is intended that the patent shall cover, by summarization in the appended claims, whatever features of the patentable novelty reside in the invention.

What is claimed is:

1. A gun-loading rig for application to a standard container holding caulking compound, grease or the like comprising a foot plate; a raised platform on the foot plate, said raised platform conforming closely to the shape of the bottom chime of a standard container for caulking compound, grease or the like; a piston; an operating rod extending upward from the piston; a cross-head connected to the foot plate, said cross-head being directly supported by and indirectly supporting the rod from the container; two upwardly extending side plates on the cross-head; rod-engaging means mounted between the side plates for progressively depressing the rod in relation to the cross-head; and, coupled to the rod-engaging means, a compound lever fulcrumed at a plurality of points intermediate its ends, the unexpended forces applied to the assembly by said lever being dissipated through said foot plate.

2. A gun-loading rig as in claim 1 in which the compound lever is made up of an actuating lever that is fulcrumed intermediate its ends and a cooperating lever that is fulcrumed intermediate its ends.

3. A gun-loading rig as in claim 2 in which the two levers have a common pivot pin located between their fulcrums.

5 4. A gun-loading rig as in claim 3 in which the fulcrum for the cooperating lever takes the form of a pintle extending between the two upwardly extending side plates on the cross-head.

10 5. A gun-loading rig for application to a standard container holding caulking compound, grease or the like comprising a piston; an operating rod extending upward from the piston; a cross-head straddling the rod for supporting the rod from the container; two upwardly extending side plates on the cross-head rod-engaging means mounted between the side plates for progressively depressing the rod in relation to the cross-head; a compound lever including an actuating lever provided with a grasping portion for transmitting force to the rod-engaging means; fastening means for the cross-head on which the side plates are mounted, such fastening means being spaced from the container; and, below the container, a foot-plate to which said fastening means are mechanically connected and by which unexpended force imposed at the grasping portion of the actuating handle is transmitted outside the rig itself, said foot plate having a raised platform characterized by a circular chime-engaging shoulder conforming closely to the shape of the bottom chime of a standard container for caulking compound, grease or the like.
